UNITED STATES PATENT OFFICE.

ARTHUR T. HALLOCK, OF TWO RIVERS, WISCONSIN.

APPARATUS FOR SORTING LUMBER, STRIPS OF MATERIAL, OR OTHER ARTICLES ACCORDING TO SIZE.

1,245,584.

Specification of Letters Patent.

Patented Nov. 6, 1917.

Application filed May 8, 1916. Serial No. 96,019.

To all whom it may concern:

Be it known that I, ARTHUR T. HALLOCK, a citizen of the United States of America, and resident of Two Rivers, Manitowoc county, Wisconsin, have invented a certain new and useful Improvement in Apparatus for Sorting Lumber, Strips of Material, or other Articles According to Size, of which the following is a specification.

10 In the manufacture of lumber for boxes, it has been customary to cut up the logs in such manner that the boards are of different widths. This has necessitated a sorting of the boards by hand, so that the boards of 15 different sizes could be used in the desired manner. Such method, of course, has involved considerable additional expense.

The object of my invention is, therefore, to provide an improved apparatus for sorting and classifying the boards so that all 20 of the boards of one width will be in one place, and all of those of a different width will be in another place, thus making it easy to handle and use the boards in the desired 25 manner, and obviating the necessity of sorting the boards by hand.

It is also an object to provide certain details and features of construction and combinations tending to increase the general 30 efficiency and desirability of a sorting and classifying apparatus of this particular character and adapted more particularly for use in sorting the comparatively small and light boards from which boxes are made.

35 To these and other useful ends, my invention consists in matters hereinafter set forth and claimed.

In the accompanying drawings:—

Figure 1 is a side elevation of an apparatus for sorting lumber or small boards, embodying the principles of my invention.

Fig. 2 is a plan of the runway of said apparatus.

Fig. 3 is an enlarged plan of the upper 45 end-portion of said apparatus, showing a portion of the apertured runway.

Fig. 4 is an enlarged section on line 4—4 in Fig. 1.

Fig. 5 is an enlarged section on line 5—5 in Fig. 3.

As thus illustrated, my invention comprises a frame or body A, of any suitable character, upon which is supported the inclined runway B, the latter being inclined 55 not only laterally, so that one side is lower

than the other, but also in such manner that one end is lower than the other, so that the boards or strips or pieces of lumber can slide down said runway by gravity, more or less, depending upon the angle of inclination. This runway has its bottom provided with a slot b formed by a series of rectangular openings 1, 2, 3, 4, 5 and 6, which openings are merged together to form the slot. Immediately above the upper end of said slot, a hopper C is mounted in position to hold a stack of boards, such as those used in making boxes. This hopper has a front wall c (see Fig. 5.) which is supported by springs 7 whereby it can yield to prevent breakage when the feed-belt D attempts to feed more than one board at a time from the bottom of the stack. The lower edge of this front wall c is disposed at the proper height to allow only one board at a time to escape from the bottom of the stack, but sometimes two boards will stick together, or the boards will be thin enough so that the lugs d on said feed-belt will engage more than one board. In such case, the front wall c will yield sufficiently to allow the two boards to pass out from under the lower edge of said wall, thus preventing 75 breakage. At its lower side, the said runway is provided with a guide E for the lower edges of the boards as they travel along the runway, being caused by gravity to bear hard against this guide. The said openings 1, 2, 3, 4, 5 and 6 are, it will be seen, of different sizes, the smallest being 80 first and the largest last, so that said slot b is larger at its lower end than at its upper end. These openings have their edges at one side of the slot in alinement, so that the slot is straight at one side, but the other 85 edge of the slot has a stepped formation because of the different widths of the several openings. This stepped side of the slot is formed by a separate strip F which forms a part of the said runway, but which is 90 adjustably connected with the other side of the runway by cross-bars f under which the boards or other articles slide down the runway. These cross-bars f have slots 9 through which the fastening-bolts 10 are inserted and which carry the longitudinal strip F, whereby the latter can be moved toward and away from the other side of the runway, thus changing the width of the slot b and thereby making it possible to handle 110

boards having a larger number of widths than those represented by the openings 1 to 6, inclusive, in a manner that will be readily understood. A belt G is mounted at the 5 lower side of the runway, and travels against the guide E to propel the boards forward by frictional contact therewith. This belt G is operated at a greater speed than the belt D, whereby each board has 10 its forward movement accelerated as it leaves the bottom of the hopper. Consequently, each board jumps ahead a distance after leaving the bottom of the hopper, and in this way the boards are separated as they 15 travel down the runway. Each board will drop through the opening of corresponding width, and as the boards are not in contact with each other at their ends, which latter are some times rough, it will not be possible 20 for any board to be held up and carried beyond its allotted opening by the other boards. Each board slides along the narrow ledge e at the base of the guide E (see the board X in Fig. 4.), and as soon as the board 25 reaches the proper opening its higher edge will drop down and the board will fall into one of the bins or compartments Y (see Fig. 1.) whereby the boards of different sizes are classified according to their width. 30 In order to avoid the necessity of getting in under the runway, in order to clean out the bins or compartments Y, inclines H are arranged in the said bins or compartments (see Fig. 4.), so that the boards falling there- 35 on will be conveyed to points at one side of the apparatus. The boards which fall on these inclines H will be discharged at the side of the apparatus, and in this way it will not be necessary to enter below the 40 runway to obtain the boards. Any suitable means may, however, be employed for receiving the boards from their respective outlets in the runway.

As shown and described, the runway B 45 is tilted downward at one end, but it may be used horizontally if such is necessary or desirable, inasmuch as the belt D may be employed for propelling the boards along the runway, so that the use of gravity will 50 not be necessary for this purpose. As shown and described, the runway is tilted to one side in order that gravity may force the lower edges of the boards against the belt G, and thus keep the boards in alinement at 55 one edge of the runway; but it is obvious that other expedients may be employed for this purpose, so that the boards may be maintained in alinement along one edge of the slot b, and that for this reason the runway 60 way is not necessarily tilted to one side, inasmuch as certain features of my invention are capable of use without tilting the runway to one side.

It will be readily understood that any 65 suitable power-transmitting-connections can

be employed for operating the belt G and the belt D for feeding the boards from the bottom of the hopper. The hopper-feeding-mechanism can also be of any suitable form or character, but the yielding front wall c 70 is a feature of improvement, and is advantageous for the reasons previously explained.

Thus, it will be seen that by my invention I provide an apparatus for classifying 75 the lumber, strips of material, or other articles, according to size. The hopper-feed-mechanism is effective in use, as the action of the yielding front wall c will prevent breakage, and also will prevent the stopping 80 of the machinery, in cases where, for any reason whatsoever, the pressure of a lug d against the lowermost board in the hopper results in pressure against the lower edge of said end wall c, which may occur 85 in different ways. For example, lumber of this kind, especially the thin boards which are made for use in the manufacture of boxes, is not of uniform thickness, and an unusually thick board might be too thick 90 to pass under the lower edge of the front wall c, if the latter were rigidly supported, but by mounting this end wall upon the springs 7, or in any other way which will enable it to yield, a thick board will finally 95 pass out from the bottom of the hopper without breaking the feed-mechanism or stopping the machinery. Again, boards of this kind are very often badly warped, and a warped board might refuse to leave the bottom of the hopper if the end wall c were rigidly mounted, whereas it will finally escape 100 from under the lower edge of this end wall when the latter is yieldingly mounted. Also, as previously explained, two or three boards 105 may stick together at the bottom of the hopper, and in such case the yielding support for the end wall c will prevent injury to the apparatus, or will tend to do this, so that breakage will be less liable. Furthermore, with the construction shown, the 110 boards of different widths are not only reliably fed onto the runway, but are also automatically discharged from the runway according to their different sizes, so that the boards of one width will all be in one bin, while the boards of another width will all be in a different bin, and so on, throughout the series of bins which are disposed below their respective openings in the runway. 115

In making boards for boxes, the method of sawing the logs is generally such that the boards are necessarily of different widths. These boards can be sorted and 120 classified by hand, but that would be slow and comparatively expensive, and with my invention the sorting is done rapidly and accurately. The boards for this purpose are usually comparatively small and light, 125

so that if the boards are allowed to engage each other at their ends, while traveling downward on the runway, they might hold each other up and prevent some of the 5 boards from falling through at the proper time. With the arrangement shown and described, however, the boards are caused to remain separate while on the runway, and do not touch each other, thus enabling even 10 very light boards to fall through the proper openings by which they are selectively discharged from the runway.

The runway B is stationary, it will be seen, during the operation of automatically 15 feeding the boards of different widths thereto. The side wall of the hopper C keeps the boards of different widths flush with each other at one side, and thus maintains these flush edges of the boards in alinement 20 with the lower side of the runway, so that the boards gradually feed downward in the hopper in alinement with the side of the runway against which the boards are maintained by any suitable provision, such as the 25 tilting of the runway sidewise to cause the boards to travel with their lower edges against the lower side of the runway.

It will be understood, however, that the sorting of lumber for boxes is only one example of the various uses for which my invention is applicable, or may hereafter be found to be applicable, and that for this reason I do not limit myself to the particular use shown and described. Also, inasmuch as the construction and mode of operation will be governed by the particular use or kind of work for which the apparatus is to be employed, I do not limit myself to the exact construction shown and described.

40 While the apparatus is shown and described as being useful for sorting boards of different widths, or other flat articles, it will be understood that I do not limit myself to any particular use, and that the general 45 combination of a runway and hopper, with the gage extending along one side of the runway, and the belt for carrying the flat articles along the runway from the hopper, can be used for any suitable or desired purpose.

What I claim as my invention is:—

1. In apparatus for sorting lumber, strips of material or other articles according to size, a runway for the articles having a plurality of openings of different widths arranged successively along said runway in the order of their size, so that the smallest opening is first and the largest last, thereby to form a series of outlets of different sizes 55 through which said articles may fall from said runway, said openings being rectangular in shape and arranged with their edges in alinement at one side of the runway and in stepped relation at the other side, and 60 said runway being tilted laterally to cause 65

said articles to slide against the side of the runway at which the edges of said openings are in alinement, a hopper also tilted laterally and disposed adjacent the smallest opening to hold a stack of said articles with one 70 side of said hopper in alinement with the lower side of said runway, and means to feed the articles from the bottom of said hopper to the runway.

2. In apparatus for sorting lumber, strips 75 of material or other articles according to size, a runway having devices to selectively discharge the articles, a hopper arranged to hold the different sized articles with their edges at one side in alinement, feed-mechanism 80 to deliver the articles from said hopper to said runway, with said edges successively in contact with one side of the runway, and means for causing separation of the articles on the runway.

3. In apparatus for sorting lumber, strips 85 of material or other articles according to size, a runway having devices to selectively discharge the articles, a hopper arranged to hold the different sized articles with their 90 edges at one side in alinement, feed-mechanism to deliver the articles from said hopper to said runway, and means for causing separation of the articles on the runway, said mechanism having a feed-belt which is operated at one speed, and said means including a feed-belt which is operated at greater speed.

4. In apparatus for sorting lumber, strips 100 of material or other articles according to size, a runway having devices to selectively discharge the articles, a hopper arranged to hold the different sized articles with their edges at one side in alinement, feed-mechanism 105 to deliver the articles from said hopper to said runway, with said edges successively in contact with one side of the runway, and means for causing separation of the articles on the runway, said mechanism and runway being inclined so that said articles travel downward thereon.

5. In apparatus for sorting lumber, strips 110 of material or other articles according to size, a runway having devices to selectively discharge the articles, a hopper arranged to hold the different sized articles with their edges at one side in alinement, feed-mechanism 115 to deliver the articles from said hopper to said runway, and means for causing separation of the articles on the runway, said means including a feed-belt which operates faster than said mechanism.

6. In apparatus for sorting lumber, strips 120 of material or other articles according to size, a runway for the articles, means to support 125 said runway in position so that said articles travel thereon with their edges lower at one side than at the other, thereby to insure alinement of the edges at the one side, said runway having devices for se- 130

lectively discharging said articles at different points along the path of travel thereof, and means to hold the different sized articles with their edges in alinement at 5 one side for feeding the articles to the receiving end of said runway.

7. In apparatus for sorting lumber, strips of material or other articles according to size, a runway for the articles, means to support said runway in position so that said articles travel thereon with their edges lower at one side than at the other, thereby to insure alinement of the edges at the one side, said runway having devices for selectively discharging said articles at different 10 points along the path of travel thereof, and inclined mechanism to hold the articles in a stack with their edges even at the one side and to feed the articles to the upper end of 15 said runway.

8. In apparatus for sorting lumber, strips of material or other articles according to size, comprising a runway having a series 20 of openings of different widths forming a single continuous slot which widens at one side only in the direction of travel of the articles thereon, and means for laterally adjusting the entire side of said runway at 25 which the slot widens to vary the width 30 thereof, the stationary side of said slot being lower than the movable side to insure alinement of the articles at one side.

9. In apparatus for sorting lumber, strips of material or other articles according to 35 size, a runway for the articles having a plurality of openings of different widths arranged successively along said runway in the order of their size, so that the smallest opening is first and the largest last, thereby 40 to form a series of outlets of different sizes through which said articles may fall from said runway, said openings being rectangular in shape and arranged with their edges in alinement at one side of the runway and 45 in stepped relation at the other side, and said runway being tilted laterally to cause said articles to slide against the side of the runway at which the edges of said openings are in alinement, a hopper also tilted laterally and disposed adjacent the smallest 50 opening to hold a stack of said articles, with one side of said hopper in alinement with the lower side of said runway, and means to feed the articles from the bottom of said hopper to the runway, said runway having means to cause the separation of the articles 55 thereon.

10. In apparatus for sorting lumber, strips of material or other articles according 60 to size, a runway for the articles having a plurality of openings of different widths arranged successively along said runway in the order of their size, so that the smallest opening is first and the largest last, thereby 65 to form a series of outlets of different sizes

through which said articles may fall from said runway, said openings being rectangular in shape and arranged with their edges in alinement at one side of the runway and in stepped relation at the other side, and 70 said runway being tilted laterally to cause said articles to slide against the side of the runway at which the edges of said openings are in alinement, a hopper also tilted laterally and disposed adjacent the smallest 75 opening to hold a stack of said articles, with one side of said hopper in alinement with the lower side of said runway, and means to feed the articles from the bottom of said hopper to the runway, said runway having 80 its lower longitudinal edge provided with a belt to cause the separation of the articles thereon.

11. In apparatus for sorting lumber, strips of material or other articles according 85 to size, a runway for the articles having a plurality of openings of different widths arranged successively along said runway in the order of their size, so that the smallest opening is first and the largest last, thereby 90 to form a series of outlets of different sizes through which said articles may fall from said runway, said openings being rectangular in shape and arranged with their edges in alinement at one side of the runway and 95 in stepped relation at the other side, and said runway being tilted laterally to cause said articles to slide against the side of the runway at which the edges of said openings are in alinement, a hopper also tilted laterally and disposed adjacent the smallest 100 opening to hold a stack of said articles, with one side of said hopper in alinement with the lower side of said runway, so that the stack of articles is held with the edges 105 even at one side thereof, means to feed the articles from the bottom of said hopper to the runway, and means whereby the upper side of said runway is adjustable, thereby 110 to change the width of said openings, said hopper being supported on the stationary lower side of said runway.

12. In apparatus for sorting lumber, strips of material or other articles according 115 to size, a runway for the articles having a plurality of openings of different widths arranged successively along said runway in the order of their size, so that the smallest opening is first and the largest last, thereby 120 to form a series of outlets of different widths through which the articles of different widths may fall from said runway, and a hopper provided with means to hold a stack of articles with their edges even at one side and having means and arranged to 125 automatically feed the articles of different widths to the receiving end of said runway.

13. In apparatus for sorting lumber, strips of material or other articles according 130 to size, a runway for the articles hav-

- ing a plurality of openings of different widths arranged successively along said runway in the order of their size, so that the smallest opening is first and the largest last, 5 thereby to form a series of outlets of different widths through which the articles of different widths may fall from said runway, and a hopper provided with means to hold a stack of articles with their edges even at 10 one side and having means and arranged to automatically feed the articles of different widths to the receiving end of said runway, and means whereby said runway is supported and held stationary during the operation of automatically feeding the articles thereto.
14. In apparatus for sorting lumber, strips of material or other articles according to size, a runway for the articles having a plurality of openings of different widths arranged successively along said runway in the order of their size, so that the smallest opening is first and the largest last, thereby to form a series of outlets of different 20 widths through which the articles of different widths may fall from said runway, and a hopper provided with means to hold a stack of articles with their edges even at one side and having means and arranged to automatically feed the articles of different widths to the receiving end of said runway, said hopper having means whereby said articles of different widths are flush with each other at one side and thereby maintained 25 in alinement with one side of the runway.
15. In apparatus for sorting lumber, strips of material or other articles according to size, a runway for the articles having a plurality of openings of different widths arranged successively along said runway in the order of their size, so that the smallest opening is first and the largest last, thereby to form a series of outlets of different 30 widths through which the articles of different widths may fall from said runway, and a hopper provided with means to hold a stack of articles with their edges even at one side and having means and arranged to automatically feed the articles of different widths to the receiving end of said runway, the sides of said openings being in alinement at one side of said runway, and said apparatus having a provision for keep- 35
16. The combination of a runway for boards or flat articles, a hopper having a means to hold a stack of articles even at one side thereof, a gage extending along 40 the runway in line with said means, and a belt to carry the articles along the runway with their edges held in alinement at one side by said gage.

Signed by me at Chicago, Illinois, this 3rd 45 day of May 1916.

ARTHUR T. HALLOCK.
